BOWLING GAME BOARD

Edward J. Francis, Paterson, N. J.

Application May 31, 1950, Serial No. 10,280

Term of patent 14 years

(Cl. D34—5)

To all whom it may concern:

Be it known that Edward J. Francis, a citizen of the United States, residing at Paterson, in the county of Passaic and State of New Jersey, has invented a new, original, and ornamental Design for a Bowling Game Board, of which the following is a specification, reference being had to the accompanying drawing, forming part thereof.

In such drawing:

Fig. 1 is a view in plan of a bowling game board, showing my new design; and

Fig. 2 is a view in side elevation of such game board.

This application is a continuation-in-part of my prior application, Serial No. D-142,451, filed November 10, 1947, now abandoned.

I claim:

The ornamental design for a bowling game board, substantially as shown.

EDWARD J. FRANCIS.
